UNITED STATES PATENT OFFICE.

CARLE C. CONWAY, OF NEW YORK, N. Y., ASSIGNOR TO HALLETT & DAVIS PIANO CO., OF BOSTON, MASSACHUSETTS, A CORPORATION OF MASSACHUSETTS.

MUSIC-PLAYING DEVICE.

1,174,231.

Specification of Letters Patent.

Patented Mar. 7, 1916.

Application filed May 25, 1911. Serial No. 629,279.

To all whom it may concern:

Be it known that I, CARLE C. CONWAY, a citizen of the United States, residing at New York, in the county of New York and 5 State of New York, have invented a new and useful Music-Playing Device, of which the following is a specification.

This invention relates to a pneumatic musical instrument and the music sheet 10 therefor. Perforated music sheets have commonly been provided with marks adjacent to the perforated notes indicating the melody.

This invention relates to the marking of 15 the music sheets in a different way so that the operator can readily distinguish the marks of the different sections of the instrument as for example, the bass and treble, and readily control the operating devices 20 so as to accent the proper notes in said sections.

Reference is to be had to the accompanying drawing in which—

Figure 1 is a diagrammatic view of a portion of a pneumatic piano action and controlling devices and showing the music sheet, and Fig. 2 is a view of a portion of the music sheet on enlarged scale.

The invention is shown as applied to an 30 ordinary type of musical instrument having bellows 10 and an action divided into a plurality of sections as bass and treble sections 11 and 12. These as usual are connected with the bellows by two chokers 13 and 14. These two chokers are controlled by pneumatics 15 and 16 to which air is admitted by the operation of a pair of movable operating elements, as buttons 17 and 18. The music sheet 20 is provided with 35 the usual note perforations 21 and with two sets of marks 22 and 23, the marks 22 indicating the notes of the bass section that are to be accented, while the marks 23 indicate the notes of the treble section that 40 are to be accented.

In order to provide for readily distinguishing the accented notes of each section of the action and for reducing error due to touching the wrong accenting button, the 45 marks 22 in the bass section are colored red while the marks 23 in the treble section are

colored blue and the button 17 controlling the bass action is colored red while the button 18 controlling the treble action is colored blue. It will be seen, therefore, that 55 the two buttons have surfaces readily distinguishable from each other and that the marks indicating the notes to be accented of each section are of the same appearance as the button for controlling that section so 60 that the operator when he sees a red mark about to pass over the tracker will know that he must press the red button, for example. In this way all confusion between the different sections of the action is avoided 65 and the operator is enabled to provide the proper accent without stopping to consider whether the note about to be accented is in the treble or bass section. It will be understood, of course, that the invention is equally 70 applicable to instruments divided in any other way.

While I have illustrated and described a preferred embodiment of the invention, I am aware that many modifications can be 75 made therein by any person skilled in the art without departing from the scope of the invention as expressed in the claims. Therefore, I do not wish to be limited to all the details of construction herein shown and 80 described but

What I do claim is:—

1. The combination with a pneumatic musical instrument having an action divided into a plurality of sections, and a movable 85 element for controlling the operation of each of said sections to accent the notes thereof, said movable elements having readily distinguishable surfaces, of a music sheet having provisions for controlling the sounding of the notes and provided with marks for indicating the notes to be accented, the marks for those notes in each section being of the same appearance as the movable element for controlling the accent of that section. 90

2. The combination with a perforated music sheet having each note perforation to be accented provided with a designative mark just in advance of, and in line with, 100 it, those in the treble and bass sections being of different distinctive colors, of a but-

ton of each of said colors, each for controlling the accent of the notes in one of said sections, and means whereby when a marked note of the sheet is coming into operative position, the depression of the button having the color of the mark of that note will cause that note to be accented.

In testimony whereof I have hereunto set my hand, in the presence of two subscribing witnesses.

CARLE C. CONWAY.
